UNITED STATES PATENT OFFICE.

GEORGE H. HUENERGARDT, OF COLLEGE VIEW, NEBRASKA.

WASHING-MACHINE.

1,113,995.

Specification of Letters Patent.

Patented Oct. 20, 1914.

Application filed December 23, 1912. Serial No. 738,329.

To all whom it may concern:

Be it known that I, GEORGE H. HUENERGARDT, a subject of the Czar of Russia, residing at College View, in the county of Lancaster and State of Nebraska, have invented 5 a new and useful Washing-Machine, of which the following is a specification.

This invention relates to washing machines and is more particularly designed as 10 an improvement upon the structure disclosed in Patent No. 832,062 issued to G. H. Huennergardt on October 2, 1906.

One of the objects of the invention is to provide a novel form of dasher having 15 means whereby the air, when trapped between the dasher and the water thereunder is distributed evenly along the bottom of the dasher so as to discharge in separate jets whereby its passage through the fabrics in 20 the machine is insured. Heretofore, where ordinary flat dashers have been used, the air has escaped along the lines of least resistance and, when fabrics have been located against the middle portions of the dashers, the air 25 has escaped around the fabrics and at the sides of the dashers, thus greatly reducing the efficiency of the machine.

One of the objects of the present invention is to overcome the disadvantages resulting 30 from the use of flat dashers.

Another object is to provide dashers which are so constructed at their active edges as to be rigid throughout the length of said edges, although formed of comparatively thin material, and which will not injure the fabrics forced thereagainst.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within 45 in the scope of what is claimed, without departing from the spirit of the invention.

In the accompanying drawings the preferred form of the invention has been shown.

In said drawings:—Figure 1 is a vertical 50 longitudinal section through a portion of a washing machine having the present improvements combined therewith. Fig. 2 is a perspective view of a dasher. Fig. 3 is a longitudinal section through the dasher. Fig. 4 is an enlarged section through the active edge portion of the dasher.

Referring to the figures by characters of reference 1 designates a substantially semi-cylindrical tub mounted to swing about an axis indicated at 2, this tub being supported in any suitable means, as by means of legs 3. Secured between the sides of the tub adjacent opposed portions, are dashers arranged in pairs, the dashers of each pair being substantially parallel. Each of the dashers is 60 preferably formed of a metallic sheet 4 having side flanges 5 adapted to be fastened to the sides of the tub 1 in any suitable manner. The dasher is provided, between these flanges, with corrugations 6, these corrugations being of considerable depth at the free or active edge of the dasher and gradually diminishing in depth back to the outer or inactive straight edge of the dasher. As shown particularly in Fig. 3, the corrugations 70 are so arranged as to extend partly above and below the plane occupied by the lower edges of the flanges 5. These corrugations obviously form channels through which the trapped air will travel while escaping from under the dasher. 75

In order that the active edge of the dasher may be reinforced and may be prevented from injuring the fabrics thrown thereagainst, the plate 4 is folded back along said 80 edge as indicated at 7 and fitted between this backwardly folded portion and the plate is a strip 8 which, in turn, is folded forwardly and downwardly around the front edge portion of the plate 4 and as 90 clearly indicated in Fig. 4. Thus it will be seen that the dasher is reinforced along its active edge and said edge portion is also thus thickened so as not to injure the fabrics thrown against it. 95

When the tub is swung back and forth about its axis 2 the water contained therein will trap air under the dashers and this air will be forced outwardly by the pressure of water thereagainst. As channels are formed along the lower faces of the dashers, the air, in escaping, will be split into separate bodies and these bodies will discharge in the form of separate jets through the fabrics abutting against the edges of the dashers. This 100 movement of the air has been indicated by arrows in Fig. 2.

What is claimed is:—

In a washing machine, the combination with a tub mounted for oscillation, of opposed dashers arranged transversely within the tub and inclined downwardly and in-

wardly, each of said dashers having a straight edge bearing against the adjacent wall of the tub and preventing leakage between the dasher and wall, each dasher also having corrugations extending from points adjacent said straight edge to the opposed free edge of the dasher, said corrugations gradually increasing in depth toward the free edge of the dasher, said corrugations

being extended substantially at right angles 10 to said straight edge.

In testimony that I claim the foregoing as my own, I have hereto affixed my signature in the presence of two witnesses.

GEORGE H. HUENERGARDT.
